UNITED STATES PATENT OFFICE.

JOHN F. O. STRATTON, OF CHICAGO, ILLINOIS.

REMOVABLE CONDENSER UNIT FOR MAGNETOS.

1,287,790.

Specification of Letters Patent.

Patented Dec. 17, 1918.

Application filed August 21, 1918. Serial No. 250,878.

To all whom it may concern:

Be it known that I, JOHN F. O. STRATTON, a citizen of the United States, and a resident of Chicago, in the county of Cook and State of Illinois, have invented certain new and useful Improvements in Removable Condenser Units for Magnetos; and I do hereby declare that the following is a full, clear, and exact description thereof, reference being had to the accompanying drawings, and to the letters of reference marked thereon, which form a part of this specification.

This invention relates to improvements in magnetos and more particularly to that part of the magneto having to do with the condenser. The function of a condenser, as is well known, is to protect the circuit breaker points of the instrument from injury by a heavy arc which would be caused if, when the current is suddenly cut, the current is permitted to pass directly to ground instead of through a condenser. For this reason, condensers are of delicate construction and require accuracy in operation and in adjustment, to properly coördinate with the magneto in use. In my invention, I make no claim to novelty in the construction of the condenser, *per se*, or in its use with a magneto, but to special features of arrangement, construction and location, as herein-after set forth.

It is the practice to install condensers in the common type of magnetos between the armature heads and in close proximity to the windings on the armature. In what is known as the rotary type of magneto, the condenser is installed within the arc of the magnets, this location being necessitated to conform to the stationary windings which, in that type of magneto, are also contained within the arc of the magnets; the rotary type being that in which the windings are stationary and in which the wings, directing the magnetic flux, revolve. With all types of magnetos in order to examine or to repair the condenser, it is necessary to take the entire magneto apart, and after examination or repair, there is always the danger

of not putting it together again precisely as it was originally.

When a magneto is giving trouble, the repair man or manufacturer will usually first suspect the condenser and will disassemble the device to get at the condenser and examine it. If it is good, he puts it back and looks for the trouble in some other part of the magneto. If it is defective, he discards it and inserts a new condenser. This requires considerable dismantling of the magneto and condenser connection, even if only to examine and not to repair the condenser. Great delicacy and nicety of adjustment is required either in restoring a condenser after examination or repair as well as when installing a new one.

It is one of the principal objects of my invention therefore, to produce a construction of magneto wherein the condenser shall be located in such part of the device as will afford ready accessibility for examination or repair, and in which the condenser shall be removably located so as to permit of its easy removal and return without the necessity of dismantling the other parts of the magneto or of exercising great care in its adjustment, and to thus obviate a serious defect in magneto construction at present very commonly existing.

Condensers have inductive capacity, or the ability to absorb a certain amount of electric energy and temporarily retain it for use in the next cycle of the armature revolution and circuit breaker opening. It is fundamental, therefore, that the closer in point of location, this storage of electrical energy is brought to the point of discharge,—the more efficient will be the inductive capacity to assist the function of the magneto. The closer a condenser is positioned with respect to the point where the arc may occur necessarily reduces the copper resistance and thus tends to promote the rapid discharge of current to the condenser as well as facilitate the use of the surplus or stored up current in the next cycle of the operation of the magneto.

The second, and equally important, object

of my invention therefore, is to locate the condenser as closely as possible to the circuit breaker of the magneto, without destroying its accessibility for examination; thereby obviating the objections just stated and promoting the efficiency of the device as a whole.

These and other objects of the invention will be more fully comprehended as I proceed with my specification.

In the drawings:

Figure 1 represents, in elevation, the spark advance end of a magneto embodying my invention, a small portion being broken 15 away.

Fig. 2 is a side elevation of the same.

Fig. 3 is a partial front elevation of the same, with the cover removed, showing the circuit breaker housing and the circuit 20 breaker also in elevation.

Fig. 4 is a perspective view of the condenser, removed.

Fig. 5 is a sectional, plan view of a part 25 of the structure, taken upon the horizontal plane indicated by the dotted line 5-5 in Fig. 6.

Fig. 6 is a vertical, sectional view of a portion of the structure taken upon the plane indicated by the dotted line 6-6 of 30 Fig. 3, looking in the direction indicated by the arrows.

Fig. 7 is a perspective view of a portion 35 of the magneto structure, with the cover and the circuit breaker parts removed, showing the condenser in position in the circuit breaker housing.

Fig. 8 is a perspective view of the slotted connecting sleeve for the contact arm of the condenser.

40 Referring now to said drawings, the magneto structure as a whole is indicated at A, that part of the frame or housing carrying the circuit breaker is indicated at B, the cover for this housing is indicated at C, and 45 the spark advance lever at D. The cover C is removably secured to the housing frame B at the top by a thin, washer-like clamp *a* placed over a suitable screw-threaded stud projecting from the face of the frame B 50 and secured to said stud by a lock nut *b*. The lower segment of the washer *a* enters a recess *c* in the top of the cover C, as shown in Figs. 1 and 2. Within the housing B is a screw threaded bolt E, the free end of 55 which projects through the cover C to receive the locking nut *e*. A suitable sleeve *e'* of rubber or other insulating material is located in the bolt aperture and surrounds the bolt E to protect it from contact with 60 the cover C. The condenser as a whole is indicated at F.

The circuit breaker housing B is a casting, L-shaped in general conformation. It

comprises a vertical wall 1 and a laterally projecting base or wall 2, an outwardly extending hub 3, and two relatively narrow vertically arranged side walls 4, 4. Two raised shoulders 5, 5, on the top surface of the base 2 extend, one on each side, from the front margin of said base wall 2 to the 70 vertical wall 1. The wall 1 of the housing B is thicker throughout its upper portion than in its lower portion, thus forming a sort of over-hanging wall 6 above the bearing hub 3. It is also provided on each side 75 near the side walls 4, 4, with suitable shoulders 7, 7, whereby a recess is formed between said shoulder and the inside face of the side wall 4.

The cover C is of irregular shape, so that 80 when placed upon the face of the housing B, a substantial chamber or open space is inclosed by said cover and said housing within which the condenser F and the circuit breaker, indicated as a whole by the 85 letter G, may conveniently be located, as more fully disclosed in Figs. 5, 6 and 7. As the circuit breaker, *per se*, is not herein claimed, the details of its construction are not material except to state, that it is oper- 90 atively mounted upon the shaft positioned within and projecting from the hub 3, and has the usual circuit breaking points 8, 8 and a condenser contact curved arm 9.

The bolt E is provided with a head 10 95 and this headed end is held and supported in a bracket 11, secured firmly to the face of the wall 1 by screw bolts 12, 12, or other suitable means. The bracket is properly insulated, first by the insulating block of rubber 13 interposed between the bracket and said wall, and then by the insulating washers 14, 14, located between the head of the bolts 12, 12, and the face of the bracket 11, as shown. The front end of this bolt E is 105 held firmly to the casing C by the nut *e*.

The condenser F may be of any standard construction contained within a metallic hermetically sealed capsule or housing, to constitute a unitary structure, as shown in Fig. 110 4. In this instance, it is of generally rectangular outline, of a height to fit nicely between shoulder 5 and the overhanging shoulder 6, of a width somewhat less than the width of the recess between the wall 4 115 and the shoulder 7, and of a length to fit nicely between the front of the wall 1 and the back of the casing C. Secured to the inside face of the shell or casing of the condenser is a curved spring arm 15, the outer or free end of which will have frictional bearing against the shoulder 7 when the condenser is seated in its home position, the spring arm thus holding the inner end of the condenser firmly against the inside surface of the side wall 4. When thus posi- 120 125

tioned, as illustrated in Figs. 3, 5, 6 and 7, in the left hand side of the circuit breaker chamber, it will be securely held in such position first by its nice frictional contact 5 with the parts just mentioned, of the housing B and cover C, and secondly by the spring arm 15 and also by the brace plate 20.

A conducting strip or contact arm 16 of copper or other suitable metal, projects laterally from the condenser and is sufficiently long to reach therefrom to and to have contact bearing against the circuit breaker contact arm 9. In order to hold this arm 16 in proper operative relation, it is passed 10 through a guide slot 17 in a tubular sleeve 18 positioned upon the bolt E. A bushing 19 of insulating material is also positioned upon the bolt E and upon the bolt, between said bushing 19 and the slotted sleeve 18 15 is a metallic brace or bar 20, the end of which has frictional bearing against the inner face of the condenser capsule. This strip 20 assists in steadyng and holding the condenser in its operative position.

25 It will be noted that the condenser is thus located in close proximity to the point in the magneto where the arc might occur, thus reducing the copper resistance detrimental to a rapid discharge of the current, 30 to a minimum. It will also be manifest that by reason of the location of the condenser in close proximity to the point of discharge, the inductive capacity of the condenser to absorb a certain amount of electric 35 energy and to effectively discharge the same to assist in the functioning of the magneto, will be materially increased.

It will also be noted that the condenser in use will be held firmly in its operative 40 position and yet that it is easily and quickly removable for inspection, test, repair or replacement. It is only necessary to remove the cover C and then to remove the insulating bushing 19 and the brace bar 20, in order 45 to slip the condenser out of its position,—the spring arm 15 readily yielding to release the inner end of the condenser from the recess between the shoulder 7 and the wall 4. Likewise, it will be understood that the re- 50 positioning of the condenser in operative position is a simple and quick operation and does not require nice adjustment,—proper adjustment being automatically attained upon pressing the condenser home and then 55 replacing the brace bar 20 and the bushing 19 and locking the cover C in proper position. The device is thus, in a sense, fool-proof, always ready for effective operation.

While slight modifications and changes 60 may be suggested by the mechanic without departing from the principle of my invention, all of which I claim within the scope thereof, I nevertheless recommend the form

of embodiment of the invention herein illustrated and described as a preferred form 65 of demonstrated practical utility in use.

I claim as my invention:

1. A magneto comprising a frame member carrying a circuit breaker, a cover for said frame member and a condenser unit 70 removably positioned within said frame member and cover and in operative relation to the circuit breaker.

2. A magneto comprising a frame member carrying a circuit breaker, a cover for said frame, a condenser unit yieldingly held 75 within said frame and cover in operative relation with the circuit breaker and removable as a unit when the cover is removed from the frame.

3. A magneto comprising a frame member carrying a circuit breaker, a cover for said frame member and a condenser unit 80 removably positioned within said frame member cover and in operative relation to the circuit breaker, a bracket secured to and insulated from the frame member, a bolt carried by said bracket and extending to the cover, and insulated means for securing the bolt to the cover.

4. A magneto comprising a frame member at one end, a circuit breaker supported thereon in operative relation to the magneto, a cover for said frame member, a condenser unit 85 removably positioned with the frame member and cover, and a metallic conductor arm secured to the condenser unit and adapted to contact with the circuit breaker.

5. A magneto comprising a frame member at one end, a circuit breaker supported 90 thereon in operative relation to the magneto, a cover for said frame member, a condenser unit removably positioned within the frame member and cover, a metallic conductor arm secured to the condenser unit and adapted 95 to contact with the circuit breaker, a bracket secured to and insulated from the frame member, a bolt carried by said bracket and extending to the cover, insulated means for securing the bolt to the cover and guiding 100 means on the bolt for the conductor arm.

6. A magneto comprising a frame member at one end, a circuit breaker supported thereon in operative relation to the magneto, a cover for said frame member, a condenser unit 115 removably positioned within the frame member and cover, a metallic conductor arm secured to the condenser unit and adapted to contact with the circuit breaker, a bracket secured to and insulated from the frame member, a bolt carried by said bracket and extending to the cover, insulated means for securing the bolt to the cover, guiding means on the bolt for the conductor arm, said means comprising a slotted sleeve on 120 said bolt.

7. In a magneto equipped with a removable condenser unit rectangular in shape, a frame member having a circuit breaker supported thereon and operatively connected with the magneto, opposing top and bottom surfaces on said frame member adapted to support opposing surfaces of the condenser unit, a side wall on the frame member, a shoulder on the frame member opposite said side wall and at a distance removed therefrom greater than the thickness of the condenser unit, and resilient means on the unit

adapted to contact with said shoulder and hold the condenser unit removably locked against said side wall.

In testimony that I claim the foregoing as my invention I affix my signature in the presence of two witnesses, this 19th day of August A. D. 1918.

JOHN F. O. STRATTON.
